UNITED STATES PATENT OFFICE.

BERT LOUGH AND ROBERT E. MILLER, OF MORGANTOWN, WEST VIRGINIA.

GAS-VALVE.

1,209,182.

Specification of Letters Patent. Patented Dec. 19, 1916.

Application filed April 27, 1916. Serial No. 94,044.

To all whom it may concern:

Be it known that we, BERT LOUGH and ROBERT E. MILLER, citizens of the United States, residing at Morgantown, in the county of Monongalia, State of West Virginia, have invented certain new and useful Improvements in Gas-Valves; and we do hereby declare the following to be a full, clear, and exact description of the invention, such as will enable others skilled in the art to which it appertains to make and use the same.

This invention relates to improvements in gas valves, and particularly to valves which are used where gas pressure is reduced at certain periods and again renewed.

One object of the invention is to provide a novel and simple valve for preventing the escape of gas, especially when the gas has been left turned on and the pressure is reduced sufficiently to put the flame out and is later renewed.

Another object is to provide a device of this character which includes a gravity valve for automatically closing the main gas passage when the gas pressure is reduced and which will prevent gas flowing through the said passage even though the main valve remains in open position.

30 A further object is to provide a device of this character in which the closing of the main gas valve after the gas pressure is returned, will automatically reset the parts so that when the main valve is again opened the parts will be in normal operative position.

Other objects and advantages will be apparent from the following description when taken in connection with the accompanying drawing.

In the drawing: Figure 1 is a vertical longitudinal sectional view through a valve made in accordance with our invention, the parts being in normal or operative position; Fig. 2 is a vertical section on the line 2—2 of Fig. 1; Fig. 3 is a vertical section on the line 3—3 of Fig. 1; Fig. 4 is a section similar to Fig. 1, but showing the parts in the position assumed when the turning plug is closed; Fig. 5 is a vertical longitudinal sectional view through a modified form of my device showing the parts in normal position; Fig. 6 is a similar section showing the parts in inoperative position; Fig. 7 is a section on the line 7—7 of Fig. 1; Fig. 8 is a

fragmentary section on the line 8—8 of Fig. 1, the member 26 being shown in elevation.

Referring particularly to the accompanying drawing, 10 represents an elongated casing through one end of which there is formed 60 a passage 11 turning upwardly as at 12 through a shoulder 13 formed in one side of a central chamber 14 in the casing. A removable plug 15 permits access to the chamber from the top thereof. In the vertical wall above the shoulder is formed a vertically extending groove 16. Extending through the casing from the opposite end is a passage 17, the same turning upwardly as at 18 from whence it extends straight inwardly and communicates with the chamber 14 at the side opposite to the shoulder. It will be noted that the inner end of the channel 17 is disposed above the shoulder 13, the purpose of this appearing later. Disposed 75 vertically through the casing, and across the upper portion of the passage 17 is a tapered plug valve 19 formed with a transverse passage 20 adapted for alinement or registry with the passage 17.

Extending from the lower portion of the opening or seat 21 in which the plug valve is arranged, to the lower portion of the chamber 14 is a passage 22, the first-named end of said passage being adapted for registry with the lower horizontal portion of the vertically disposed and substantially Z-shaped passage 23 formed in the lower portion of the plug. A passage 24 extends from the curved portion 18 of the 80 passage 17 to the seat 21 in position to register with the upper horizontal portion of the passage 23. A third inclined passage 25 establishes direct communication between the passage 17 and the chamber 14, at a point above the passage 22. Disposed for 85 vertical sliding movement in the chamber 14 below the shoulder, is a piston 26, the same having a suitable washer 27 secured to its lower face to prevent escape of gas therearound. On the upper side of the piston is a vertical member 27' on one side of which is formed a laterally extending arm 28 having its end reduced as at 29 and movable within the before-mentioned groove 16. 90

On the lower face of this arm is a rubber ball valve 30 adapted to be seated within the upper end of the vertical portion 12 of the passage 11.

In normal or operative position the parts 110

are as shown in Fig. 1. Gas pressure enters the valve through the passage 17, flows through this passage, across the chamber 14 and down and out the passage 11. Some 5 gas also passes through the passage 25 below the piston 26 and holds the piston in elevated position so that the valve 30 is offset. It will of course be understood that the passage 20 is alined with the passage 17 on opposite sides of the plug to permit the flow of 10 gas therethrough. When the pressure of gas is reduced or removed, and the plug valve 19 remains in open position, the gas below the piston will be forced up through the passage 25 and out through the passage 17, this gas being forced by the downward movement, by gravity, of the piston 26. When this piston falls to the limit of its 15 downward movement, the ball valve 30 will be seated within the upper end of the passage 12. The piston drops far enough to close the inner end of the passage 25 so that should the gas pressure return it could not get below the piston so as to raise it. Also 20 by reason of the fact that the valve 30 is on its seat, the gas that passes into the chamber above the piston assists in holding the valve to its seat. Thus the danger of gas escaping by the return of the pressure is eliminated. 25

To restore the parts to normal working position, the plug 19 is first turned so as to move its passage 20 out of alinement with the passage 17. This brings the upper end 30 of the passage 23 in registry with the passage 24 and the lower end in registry with the passage 22. It will be noted that the chamber end of the passage 22 is below the piston when the said piston is in its lowermost position. This position of the valve 19 permits 35 gas to pass from the passage 17 through the plug by means of the passage 23 to a position beneath the piston to cause the piston to rise and unseat the valve 30. This will raise 40 the piston above the inner end of the passage 25 and thus permit gas from the passage 17 to flow beneath the piston and hold the same in elevated position. The plug valve 19 can 45 then be turned into open position and gas passed through the casing as first described. 50

Referring particularly to Figs. 5 and 6 there is shown a similar casing 10' having the passages 11' and 17' similar to those of the first form, except that the passage 11' 55 communicates, at its inner end with a vertical passage-way 31, this passage establishing communication between an upper chamber

32 and the lower chamber 14'. The passage 17' communicates with the upper chamber while an inclined passage 25' connects this 60 before-named passage with the chamber 14' above a passage 22' which connects the chamber 14' with the lower end of the passage 23' in the valve plug 19'. A passage 24' similar in construction and operation to 65 the passage 24 is also provided. The lower end of the chamber 14' is closed by a removable screw plug 33. The piston 26' has a stem 27' extending upwardly through the passage 31, and on the upper end of this stem 70 is an inverted conical valve 34 which engages with a conical seat 35 in the bottom wall of the upper chamber 32. The operation of this form is identical with that of the other form and the result obtained is the same. 75 The only practical difference between this form and the previous form is in the exact construction and arrangement of the central chamber and the piston valve.

What is claimed is:—

80 An automatic gas pressure valve comprising an elongated casing having longitudinally extending inlet and outlet passages offset with respect to each other, one end of the casing having a vertical chamber formed 85 therein, a turning plug mounted in the other end of the casing, an inclined passage connecting the inlet passage with the lower portion of the chamber, a horizontal passage connecting the valve seat with the chamber 90 below the first passage, said first passage extending around the valve and out of communication with the seat, said plug having a substantially Z-shaped passage extending longitudinally therethrough and arranged 95 to have its lower end in registry with the said horizontal passage at times, a short inclined passage arranged to register with the upper end of the Z-shaped passage at times, and communicating with the inlet passage, a 100 vertically movable gravity piston mounted in the chamber and arranged to close the adjacent end of the inclined passage at times, a valve member carried by the piston for controlling the inner end of the outlet passage, 105 said valve also having a transverse passage for registration with the inlet passage.

In testimony whereof, we affix our signatures in the presence of two witnesses.
